Primary Examiner—Stella Reid*Assistant Examiner*—Mark Goodwin(74) *Attorney, Agent, or Firm*—Tsugihiko Suzuki(57) **CLAIM**

The ornamental design for a carton for bottles, as shown and described.

DESCRIPTION

FIG. 1 is a perspective view of a carton for bottles showing my new design;

FIG. 2 is a top plan view thereof;

FIG. 3 is a bottom plan view thereof;

FIG. 4 is a right side elevation view thereof; the left side elevation being a mirror image thereof; and,

FIG. 5 is a front elevation thereof; the rear elevation being a mirror image thereof.

The broken lines in FIGS. 1, 2 and 5 are for illustrative purposes only and form no part of the claimed design.
